Primary Examiner — Richard Edgar*Assistant Examiner* — Sharon H Schwartz(74) *Attorney, Agent, or Firm* — Kevin Schraven; Anooj Patel; Hankin Patent Law, APC(57) **CLAIM**

The ornamental design for a stationary bicycle shoe, as shown and described.

DESCRIPTION

FIG. 1 is a top perspective view of a stationary bicycle shoe showing my new design.

FIG. 2 is a bottom perspective view thereof.

FIG. 3 is a front elevational view thereof.

FIG. 4 is rear elevational view thereof.

FIG. 5 is an outer-side elevational view thereof.

FIG. 6 is an inner-side elevational view thereof.

FIG. 7 is a top plan view thereof; and,

FIG. 8 is a bottom plan view thereof.

The broken lines showing stitching are a claimed feature of the design. The other broken lines on the bottom are portions of the stationary bicycle shoe and form no part of the claimed design.

1 Claim, 8 Drawing Sheets
